SIDE CONSTRUCTIONS FOR RAILWAY FREIGHT CARS

Wilfred A. Beauchamp, Chicago, Ill., assignor to The Youngstown Steel Door Company, Cleveland, Ohio, a corporation of Ohio

Application July 2, 1953, Serial No. 365,720

16 Claims. (Cl. 105—409)

This invention relates to side constructions for railway freight cars and more particularly to the construction of sides for box or house cars adjacent to the door openings formed in the car sides.

It is an object of this invention to provide steel-sheathed side constructions for railway box cars which shall be capable of resisting stresses imposed thereon adjacent to the door opening formed in said constructions as a result of forces acting upon the cars and causing lengthwise movement of the upper portion of the side constructions relative to the side sills so as to resist breaking of side sills of the cars adjacent to the door openings.

A further object is to provide car side constructions of the character indicated above which shall eliminate the gussets heretofore used to connect the door posts of car side constructions to the side sills of car underframes.

A further object is to provide car side constructions for railway box cars which shall embody door posts, portions of which shall extend along and be secured to the side sills of the car underframes in the door openings so as to reinforce the side sills against breakage.

A further object is to provide car side constructions for railway box cars which shall embody door posts, portions of which shall extend along and be secured to the side plates of the car in the door openings so as to reinforce the side plates against breakage.

A further object is to provide side constructions for railway box cars which shall embody side sills and door posts secured to the side sills and so constructed and arranged as to resist breaking of the side sills adjacent to the door openings.

A further object is to provide door posts for car side constructions for railway box cars which shall embody vertical inclined stress carrying members.

A further object is to provide door posts for car side constructions for railway box cars which shall embody a plate member one margin of which is formed into an angular, vertically inclined stress carrying member.

A further object is to provide door posts for car side constructions for railway box cars which shall embody a plate member one margin of which carries an angular, vertically inclined stress carrying member wherein the plate member is so constructed and arranged that it can be secured directly to the side sill structure of the cars and thereby eliminate the separate gusset members heretofore required.

A further object is to provide door posts for car side constructions for railway box cars which shall be wider than usual so as to be capable of receiving wide removable nailing members and thereby prevent nailing and damage to the tongue and groove lining boards of such cars.

Other objects of this invention will become clear as the description thereof proceeds.

In the drawings forming part of this specification:

Fig. 1 is a fragmentary elevation of a side construction embodying the instant invention, parts being broken away.

2

Fig. 2 is a vertical section taken on line 2—2 of Fig. 1. Fig. 3 is a vertical section taken on line 3—3 of Fig. 1. Fig. 4 is a vertical section taken on line 4—4 of Fig. 1. Fig. 5 is a vertical section taken on line 5—5 of Fig. 1. Fig. 6 is a horizontal section taken on line 6—6 of Fig. 1.

Fig. 7 is a horizontal section taken on line 7—7 of Fig. 1.

The car side construction illustrated in the drawings is designated as a while by the reference numeral 10. This construction embodies the usual substantially Z-shaped side plate 11 and angle side sill 12 which extend substantially the entire length of the side, Z-shaped intermediate posts, two of which are indicated at 13 and 14, extending between and secured to the side plate and side sill, and metallic sheathing 15 extending between and secured to the side plate, side sill and intermediate posts. The side sill 12 is reinforced by a channel 16.

The car side construction also embodies similar door posts 17 and 18 which extend between and are secured to the side plate 11 and side sill 12. According to the instant invention the door posts 17 and 18 comprise vertically extending substantially channel-shaped members 19 and 20 and plate members 21 and 22 to which the channel-shaped members 19 and 20 are secured, as by means of rivets.

The door post members 19 and 20, which define the sides of a door opening 23, extend continuously between the side plate and side sill. At the side sill portions of the flanges 24, 25 and 26, 27 of these members are cut away and the remaining portions and the webs 28 and 29 of these members are bent inwardly toward the door opening 23 and away from the plate members 21 and 22 and extended along and secured to the side sill, as by means of welding, in the door opening. The portions of the members 19 and 20 which extend along the side sill thus cooperate with the vertical and horizontal legs 30 and 31 of the sill to provide a box section which substantially reinforces the sill adjacent to the door posts and prevents breaking of the sill.

At the side plate 11 the vertical channel-shaped members 19 and 20 of the door posts are bent inwardly toward the door opening 23 and away from the plate members 21 and 22 and extended along the side plate to which the extended portions are secured, as by means of welding. A portion of the flanges 24 and 26, a portion of the webs 28 and 29 and the flanges 25 and 27, are cut away from the extended portions of the members 19 and 20. The flanges 24 and 26 are secured, as by rivets, to the inner face of the depending flange 32 of the side plate, and the webs 28 and 29 extend inwardly below the web 33 of the side plate and are secured, as by means of welding, to a side plate reinforcing member 34 riveted to the upstanding flange 35 of the side plate. The side plate is thereby reinforced against breaking adjacent to the door posts since a sturdy box section is provided.

The plate members 21 and 22 of the door posts extend upwardly to the web 33 of the side plate and are secured to the inner face of the depending flange 32 of the side plate as by means of rivets, filler plates 36 and 37 being interposed between the plate members and flange 32. The plates 21 and 22 extend downwardly and outwardly of the side sill 12 and side sill reinforcing channel 16 and are secured to these members, as by means of rivets, thereby providing a sturdy connection and base for the door posts. The effectiveness of this connection and base of the door posts is materially enhanced by the construction of the plates whereby vertically, inclined marginal portions 38 and 39 are provided thereon which obtain broad bases 40 and 41 and greater resistance to longi-

tudinal movement of the side constructions under car impact. This construction, moreover, resists breaking of the side sills adjacent to the door posts.

To provide a sturdy construction for the inclined marginal portions 38 and 39, which have upwardly converging relationship with the channel-shaped members 19 and 20, for the purposes noted, these marginal portions are flanged inwardly as indicated at 42 and 43 at substantially a right angle to the plate members 21 and 22 and then outwardly substantially parallel with the plate members as indicated at 44 and 45. These flanges cooperate with the plate members to provide in effect sturdy, substantially Z-shaped sections 46 and 47 which reinforce the plate members and are capable of carrying stresses of compression and tension. As illustrated in the drawings the Z-shaped sections are inclined and converge upwardly relative to the channel-shaped members 19 and 20 of the door posts.

As shown in Figs. 1-5 the flanges 42, 43, 44 and 45 extend continuously from the horizontal flange 31 of the side sill 12 to the web 33 of the side plate 11. At the vertical flange 39 of the side sill the plate members 21 and 22 are notched as indicated at 48 and 49 to permit the flanges 42, 43, 44 and 45 to lie inwardly of the vertical flange 39 and the plate members to extend downward on the outside of this flange and the side sill reinforcing member 16.

The opposite margins 50 and 51 of the plate members 21 and 22 are provided with flanges 52 and 53 which extend outwardly at substantially a right angle to the plates and provide bases for the attachment of spark strips and front door stops (not shown). The flanges 52 and 53 extend continuously from the lower edge of the depending flange 32 of the side plate to the lower edges of the bases 40 and 41 and serve also to reinforce the plate members. At the side plate the flanges 52 and 53 are cut away as shown at 54 and 55.

It will be apparent from the foregoing description that the instant invention provides a novel door post construction which affords a sturdy base and which substantially resists breaking of the side sills of railway box cars adjacent to the door posts. By the formation on the door posts of inclined angularly shaped marginal portions great resistance is offered to the movement of the car side construction resulting from car impact and the like and the tendency of the side sills to break adjacent to the door posts is further minimized.

Moreover, the greater width of door post provided by the instant invention obtains a substantial increase in the width of nailing members shown diagrammatically at 56 and 57 secured to the door posts in any desired manner. Damage to the tongue and groove lining boards shown diagrammatically at 58 is thereby prevented when grain boards are nailed to the nailing members and a substantial economy of operation is obtained.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway box car having a side construction embodying a side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the oppo-

site marginal portion of said plate member having an angular vertically inclined section extending therealong, said section and said angular member converging from the side sill to the side plate.

5 2. In a railway box car having a side construction embodying a side sill, a reinforcing member secured to said side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the opposite marginal portion of said plate member having an angular vertically inclined section extending therealong, said section and said angular member converging from the side sill to the side plate, said plate member extending downwardly below said angular section and being secured to said side sill and side sill reinforcing member.

10 3. In a railway box car having a side construction embodying a side sill provided with an upstanding flange, a reinforcing member secured to said side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the opposite marginal portion of said plate member having an angular vertically inclined section extending therealong, said section and said angular member converging from the side sill to the side plate, said angular section terminating at the side sill, the lower portion of said angular section being separated from said plate member and disposed inwardly of said upstanding flange of said side sill and being secured to said side sill, said plate member extending downwardly below said angular section in overlapping relation with and being secured to said upstanding flange of said side sill and said reinforcing member.

15 4. In a railway box car having a side construction embodying a side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the opposite marginal portion of said plate member having an angular vertically inclined section extending therealong, said section and said angular member converging from the side sill to the side plate, said angular member being turned into said door opening at said side sill and extended along and secured to said side sill in said door opening.

20 5. In a railway box car having a side construction embodying a side sill, a side plate, and intermediate posts and sheathing extending between and secured to the side sill and side plate, metallic door posts extending between and secured to the side sill, side plate, and sheathing and defining the sides of a door opening

formed in the side construction, each of said door posts comprising a vertical channel-shaped member having inner and outer legs and a web disposed contiguous with the door opening and a plate member wider than said channel-shaped member and extending between and secured to the side sill and side plate, said outer leg of said channel-shaped member being secured to and along one marginal portion of said plate member, said channel-shaped member extending between the side sill and side plate, the opposite marginal portion of said plate member having an angular, vertically inclined section, said section and said channel-shaped member converging from the side sill to the side plate, said side sill having an upstanding flange and an inwardly extending flange, said channel-shaped member being turned into the door opening at said side sill and extended along said side sill in the door opening so that said web of said channel-shaped member is spaced from said inwardly extending flange of said side sill and said legs extend downwardly, said outer leg being secured to said upstanding flange of said side sill and said inner leg being secured to said inwardly extending leg of said side sill.

6. In a railway box car having a side construction embodying a side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the opposite marginal portion of said plate member having an angular vertically inclined section extending therealong, said section and said angular member converging from the side sill to the side plate, said angular member being turned into said door opening at said side plate and extended along and secured to said side plate in the door opening.

7. In a railway box car having a side construction embodying a side sill, a side plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical channel-shaped member having inner and outer legs and a web disposed contiguous with the door opening and a plate member wider than said channel-shaped member and extending between and secured to the side sill and side plate, said outer leg of said channel-shaped member being secured to and along one marginal portion of said plate member, said channel-shaped member extending between the side sill and side plate, the opposite marginal portion of said plate member having an angular, vertically inclined section, said section and said channel-shaped member converging from the side sill to the side plate, said side plate having an upstanding flange, an outwardly extending flange, a vertical flange depending therefrom, and a reinforcing member secured to and depending from the upstanding flange, said inner leg and a portion of said outer leg and web of said channel-shaped member being removed at said side plate and said web and outer leg thereof being turned into the door opening at said side plate and extended along said side plate in the door opening so that said web is spaced from said outwardly extending flange of said side plate and said outer leg extends upwardly, said outer leg being secured to said vertical flange of said side plate and said web being secured to said reinforcing member.

8. In a railway box car having a side construction embodying a side sill provided with an upstanding flange, a reinforcing member secured to said side sill, a side

plate, and intermediate posts and sheathing extending between and secured to the side sill and side plate, metallic door posts extending between and secured to the side sill, side plate, and sheathing and defining the sides of a door opening formed in the side construction, each of said door posts comprising a vertical angular member disposed contiguous with the door opening and a plate member wider than said angular member extending between and secured to the side sill and side plate, said angular member being secured to and along one marginal portion of said plate member and extending between the side sill and side plate, the opposite marginal portion of said plate member having an angular vertically inclined section extending therealong, said section and said angular member converging from the side sill to the side plate, said angular section terminating at the side sill, the lower portion of said angular section being separated from said plate member and disposed inwardly of said upstanding flange of said side sill and being secured to said side sill, said plate member extending downwardly below said angular section in overlapping relation with and being secured to said upstanding flange of said side sill and said reinforcing member, said angular member extending into the door opening at said side sill and extending along and secured to said side sill in said door opening.

9. A metallic door post for railway box car side constructions having a side sill structure at the bottom thereof and a side plate at the top thereof, said door post comprising an angular member having inner and outer legs and a connecting web and a plate member wider than said angular member, said angular member being secured to and along one vertical marginal portion of said plate member, the opposite marginal portion of said plate member being inclined and bent to provide an inwardly extending inclined flange and an inclined flange extending at an angle from said latter flange whereby said opposite marginal portion has an inclined angular section, said angular section and said angular member converging upwardly, said door post when assembled in said side constructions extending between and being secured to said side sill structure and said side plate.

10. A metallic door post for railway box car side constructions having a side sill structure at the bottom thereof and a side plate at the top thereof, said door post comprising an angular member having inner and outer legs and a connecting web and a plate member wider than said angular member, said angular member being secured to and along one vertical marginal portion of said plate member, the opposite marginal portion of said plate member being inclined and bent to provide an inwardly extending inclined flange and an inclined flange extending at an angle from said latter flange whereby said opposite marginal portion has an inclined angular section, said angular section and said angular member converging upwardly, said door post when assembled in said side constructions extending between and being secured to said side sill structure and said side plate, said angular member and said angular section terminating above the bottom of said plate member.

11. A metallic door post for railway box car side constructions having a side sill structure at the bottom thereof and a side plate at the top thereof, said door post comprising a substantially channel-shaped member having inner and outer legs and a connecting web and a plate member wider than said channel-shaped member, said outer leg of said channel-shaped member being secured to and along one vertical marginal portion of said plate member, the opposite marginal portion of said plate member being inclined and bent to provide an inwardly extending inclined flange and an inclined flange extending at an angle from said latter flange and cooperating therewith and with the adjacent portion of said plate member to provide an inclined Z-shaped section, said channel-shaped member and said Z-shaped section converging

upwardly, said door post when assembled in said side constructions extending between and being secured to said side sill structure and said side plate.

12. A metallic door post for railway box car side constructions having a side sill structure at the bottom thereof and a side plate at the top thereof, said door post comprising an angular member having inner and outer legs and a connecting web and a plate member wider than said angular member, said angular member being secured to and along one vertical marginal portion of said plate member, the opposite marginal portion of said plate member being inclined and bent to provide an inwardly extending inclined flange and an inclined flange extending at an angle from said latter flange whereby said opposite marginal portion has an inclined angular section, said angular section and said angular member converging upwardly, said door post when assembled in said side constructions extending between and being secured to said side sill structure and said side plate, the upper and lower ends of said angular member being bent away from said plate member.

13. A metallic door post for railway box car side constructions having a side sill structure at the bottom thereof and a side plate at the top thereof, said door post comprising a substantially channel-shaped member having inner and outer legs and a connecting web and a plate member wider than said channel-shaped member, said outer leg of said channel-shaped member being secured to and along one vertical marginal portion of said plate member, the opposite marginal portion of said plate member being inclined and bent to provide an inwardly extending inclined flange and an inclined flange extending at an angle from said latter flange and cooperating therewith and with the adjacent portion of said plate member to provide an inclined Z-shaped section, said channel-shaped member and said Z-shaped section converging upwardly, said door post when assembled in said side constructions extending between and being secured to said side sill structure and said side plate, the upper and lower ends of said channel-shaped member being bent away from said plate member.

14. A metallic door post for railway box car side constructions having a side sill structure at the bottom thereof and a side plate at the top thereof, said door post comprising a substantially channel-shaped member having inner and outer legs and a connecting web and a plate member wider than said channel-shaped member, said outer leg of said channel-shaped member being secured to and along one vertical marginal portion of said plate member, the opposite marginal portion of said plate member being inclined and bent to provide an inwardly extending inclined flange and an inclined flange extending at an angle from said latter flange and cooperating therewith and with the adjacent portion of said plate member to provide an inclined Z-shaped section, said channel-shaped member and said Z-shaped section converging upwardly, said door post when assembled in said side constructions extending between and being secured to said side sill structure and said side plate, said channel-shaped member and said Z-shaped section terminating above the

bottom of said plate member, the lower portion of said inwardly extending flange of said Z-shaped section being separated from said plate member.

15. A metallic door post for railway box car side constructions having a side sill structure at the bottom thereof and a side plate at the top thereof, said door post comprising an angular member having inner and outer legs and a connecting web and a plate member wider than said angular member, said angular member being secured to and along one vertical marginal portion of said plate member, the opposite marginal portion of said plate member being inclined and bent to provide an inwardly extending inclined flange and an inclined flange extending at an angle from said latter flange whereby said opposite marginal portion has an inclined angular section, said angular section and said angular member converging upwardly, the lower end of said angular member being bent away from said plate member, said plate member extending downwardly below said angular member and said angular section, said inwardly extending flange on said plate member being separated from said plate member, said door post when assembled in said side constructions extending between and being secured to said side sill structure and said side plate.

16. A metallic door post for railway box car side constructions having a side sill structure at the bottom thereof and a side plate at the top thereof, said door post comprising an angular member having inner and outer legs and a connecting web and a plate member wider than said angular member, said outer leg of said angular member being secured to and along one vertical marginal portion of said plate member, the opposite marginal portion of said plate member being inclined and bent to provide an inwardly extending inclined flange and an inclined flange extending at an angle from said latter flange whereby said opposite marginal portion has an inclined angular section, said angular section and said angular member converging upwardly, the lower end of said angular member being bent away from said plate member, said door post when assembled in said side constructions extending between and being secured to said side sill structure and said side plate.
